**ADHESIVELY MOUNTED COMBINED EYEGLASS
AND COIN HOLDER**

Harry T. Reed, Kansas City, Mo., assignor to Smith &
Reed Enterprises, Inc., Kansas City, Mo.

Filed May 16, 1972, Ser. No. 253,919

Term of patent 14 years

Int. Cl. D16—06; D3—02

U.S. Cl. D57—1 C

*Fig. 1**Fig. 2**Fig. 3**Fig. 4*FIG. 1 is a perspective view of an adhesively mounted combined eyeglass and coin holder showing my new design;

FIG. 2 is a top plan view thereof;

FIG. 3 is a rear elevational view thereof; and

FIG. 4 is an end elevational view thereof.

The broken lines are shown in FIGS. 1 and 2 for illustrative purposes only.

I claim:

The ornamental design for an adhesively mounted combined eyeglass and coin holder, as shown and described.
